CLIP FOR PAPER MONEY AND THE LIKE

Carl C. Wilm, Denver, Colo., assignor to Magnex, Inc.,
Denver, Colo., a corporation of Colorado

Application December 16, 1955, Serial No. 39,354

Term of patent 14 years

(Cl. D17—3)

Figure 1 is a plan view of the clip, showing my new design in open position. Fig. 2 is a side elevational view thereof, and Fig. 3 is an isometric view of the clip when in closed position.

The side opposite that shown in Fig. 1 is substantially plain.

I claim:

The ornamental design for a clip for paper money and the like, substantially as shown and described.
